UNITED STATES PATENT OFFICE.

HENRY G. KRESS, OF MANITOWOC, WISCONSIN.

GAS-ENGINE.

1,189,834.

Specification of Letters Patent.

Patented July 4, 1916.

Application filed August 6, 1915. Serial No. 44,084.

To all whom it may concern:

Be it known that I, HENRY G. KRESS, a citizen of the United States, and resident of Manitowoc, in the county of Manitowoc and State of Wisconsin, have invented certain new and useful Improvements in Gas-Engines; and I do hereby declare that the following is a full, clear, and exact description thereof.

10 My invention has for its primary object to provide a simple, effective and economical gas engine of the internal combustion type, its construction and arrangement being such that a piston having oscillatory motion converts said movement into rotary motion and the rotary motion may be rendered continuous by employing a series of such pistons, either arranged on a common plane or in a parallel series. In either case movement of 15 the series of pistons is imparted to a rotor by a one-way clutch mechanism preferably of the friction type.

With the above objects in view the invention consists in certain peculiarities of construction and combination of parts as hereinafter set forth with reference to the accompanying drawings and subsequently claimed.

In the drawings Figure 1 represents a sectional elevation of a simple form of engine embodying the features of my invention, the section being indicated by line 1—1 of Fig. 2; Fig. 2, a cross-section of the same, the section being indicated by line 2—2 of Fig. 1; Fig. 3, a detailed sectional view through the valve-actuating mechanism, the section being indicated by line 3—3 of Fig. 1; Fig. 4, a detailed cross-section through the exhaust ports of the stator; Fig. 5 represents an elevation of an engine embodying another form of my invention with parts broken away and in section to show details of construction; and Fig. 6, a cross-section of the same, the section being indicated by line 6—6 of Fig. 5.

Before explaining the construction of the engine as shown in the drawings, I wish to call attention to the fact that the exemplification disclosed simply illustrates one manner in all its details for carrying out my invention and the drawings show only a single piston and its associated mechanism, together with a simple valve mechanism which forms no part of my invention specifically as any valve mechanism suitable for the purpose may be employed, the single

unit shown in the drawings being considered sufficient to illustrate the principles upon which the engine can be built, bearing in mind that the piston units can be increased indefinitely to provide the predetermined horse power.

Referring by characters to the drawings, 1 represents a stator having a segmental chamber 2 therein in the form of a segment of a circle and a circular slot 3 extending therethrough. The stator, as shown, is supported by a suitable frame 4, which rises from a base-plate. A shaft 5 is journaled at the axis of the segmental chamber of said 60 stator and extends in opposite directions from the walls of the same, one end of the shaft being also supported by a bearing 4' which constitutes part of the frame 4. The outer circular edge of the piston engages 65 the inner circular wall of the stator chamber whereby a tight joint is effected, which tight joint may be rendered further efficient by the provision of packing rings associated with the piston, which are not shown.

A rotor 7 in the form of a ring is mounted to rotate about the outer circular face of the stator and said rotor is also formed with spider arms 7' which connect the outer part thereof with a hub portion 8, the said hub portion being revolvably mounted upon the shaft 5, whereby the piston and rotor are axially aligned. The hub 8 is further supported by a bearing 4'' that constitutes part 70 of the supporting frame 4. The rotor comprises the means whereby power from the engine may be transmitted to any machine element and in order to transmit said power any means may be connected with said rotor, that shown being a toothed wheel 9, 75 which wheel is secured to the end of the hub 8. It is manifest that, in some instances, the ring portion of the rotor may constitute a belt pulley, but such details 80 form no part of my present invention.

In order to transmit power from the piston to the rotor 7, said piston is provided with a socket 10, which forms a seat for one end of a knuckle block 11. The knuckle block extends into the slot 3 of the stator and its upper end is seated in a socket 105 formed in a friction shoe 12, which shoe is adapted to engage the inner circular wall of the rotor. The knuckle block is positioned at such an angle with relation to the direction of movement of the rotor (as indicated by the arrow), that when the piston

moves in said direction the outer end of the knuckle block 11 will describe a slight arc movement with relation to its fulcrum point at the opposite end, whereby the shoe 12 will be forced outwardly and thus tightly clamp against the juxtaposed wall of the rotor, whereby said rotor and piston are locked securely together, this connection being made through the slot 3. Hence, when 5 the piston moves from right to left, it will impart a corresponding movement to the rotor, while, upon a reverse movement of the piston, the knuckle block will drop back, whereby the shoe will disengage the rotor 10 and said rotor will thus be fed forward a distance equal to the stroke of the piston, while the piston upon its return stroke will move idly. Thus an intermittent feed movement is imparted to the rotor by the forward movement of said piston, while the reverse movement of said piston may be considered an idle movement. 15

In order to provide some means for introducing fuel gas to the opposite ends A. 20 B. of the chamber, I provide ports 14, 14', the latter being somewhat smaller for the reason that the charge of gas introduced therethrough is, in this exemplification of my invention, simply for the purpose of returning the piston after it has completed its working stroke. Each port is provided with a spring-seated valve 15 having stems 16 which are engaged by the ends of valve levers 17, 17'. These valve-levers, as shown, 25 are fulcrumed in ears 18 which depend from the bottom wall of the stator and said valve-levers are held in engagement with the valve stems by delicate leaf springs 19, which extend from the ears 18 and engage the inner arms 20, 20', of the levers. The inner ends of each of these arms are upturned and are provided with oppositely extended cam webs 21, 21', which are spaced apart to permit an arm 22 to pass therebetween, which arm 30 is rigidly secured to the sleeve 28 and constitutes a piston-arm having a tappet-pin 23 at its end, which projects in opposite directions and is adapted to engage the cam webs. A manifold pipe 24 communicates 35 with the valve ports 14 and 14' in the ordinary manner and, as shown, said manifold pipe is provided with valves 24', whereby the supply of fuel gas may be regulated. Thus it will be seen that the piston in effect 40 divides the chamber 2 into compartments A, B. Between the compartments A and B there is a main exhaust port 25 that communicates with a pipe C and said exhaust port is provided with leads extending in opposite directions which communicate with auxiliary ports 25', 25'' that communicate 45 respectively with the compartments B, A. I have also shown a spark-plug 26 in connection with each compartment of the stator and said spark-plugs may be suitably

connected to a source of electrical energy, whereby they will ignite the charge of gas introduced into their respective compartments when the rotor has completed what might be termed its compression movement. 50

The gas which is admitted to the chambers A and B through the ports 14 and 14' is under a constant pressure, which pressure may be obtained in any suitable manner, and the valves are so timed with respect to 55 their operation by the piston arm 22 that they open to admit the gas to each respective chamber when the respective chamber wall is in a position intermediate of the stator wall and the respective exhaust port. The 60 gas is thus further compressed by the piston during its movement from such intermediate position to the position at which explosion occurs. Although it is true that the 65 exhaust port of the chamber is closed during the initial movement of the piston in what might be termed compression movement, such burned gases as there exist in the 70 chamber would be at a pressure no greater than atmospheric pressure and consequently 75 would not interfere substantially with the explosive charge of the chamber. This condition of a certain amount of burned gas remaining in a chamber is present in nearly 80 all types of two-cycle engines. 85

Having described the engine in detail, it will be apparent that, when the piston is in the position shown in Fig. 1, gas has previously been admitted through the valve-controlled port 14 and said gas charge is 90 under compression. The charge is then ignited and expansion of said exploded charge will cause the piston to move from right to left, carrying with it the rotor, thus imparting to the same a working stroke. Before 95 the face *a* of the piston has completed the stroke, it will be observed that the tappet of arm 22 will abut the upturned end of the arm 20' of valve lever 17', whereby the valve-lever is moved to cause the valve 15 100 to lift and a small charge of gas is admitted to the compartment B. After the tappet 23 passes the end of said arm 20', the spring-controlled valve 15 will again seat and thus the charge of gas admitted to said 105 chamber will be compressed as the wall *a* of the piston retards its movement. Coincident to the completion of this compression movement of the piston face, the piston face *b* will move into register with the auxiliary exhaust port 25'', whereby the spent 110 gases in the chamber A will be exhausted through said port. The piston having completed its working stroke, it will be manifest that the auxiliary charge of gas which 115 has been compressed in the compartment B will be exploded and thus the piston will move upon its idle stroke from left to right and in so doing the tappet 23 of the piston arm 22 will engage the upturned end of 120

125 130

the valve-lever arm 20, whereby a charge of gas is admitted to the compartment A through the movement of the lever 17 which will thus lift the valve 15 from its seat. In 5 performing this function the tappet 23 will pass under the cam web 21' of lever 17' and lift said lever slightly in opposition to its spring pressure, but this movement is idle in function and will not affect the valve 15. 10 The same idle movement of the valve lever 17 is effected when the arm 22 moves from left to right while the piston is upon its working stroke and the tappet 23 passes under the cam web 21 so as to be in the 15 proper position to operate the lever 17 when the movement of said arm is reversed. Thus the valve-levers 17 and 17' are alternately manipulated to admit charges of gas to the compartments A, B, and said charges are 20 alternately exploded and the spent gases are alternately exhausted from the chamber 2 through the auxiliary exhaust ports 25' 25''. It is obvious that the shaft 5 may be extended and that a series of engine units such as 25 I have described may be affixed to said shaft and the explosion so timed that the movements of the series of pistons will continuously revolve the rotor.

It is also apparent that, in place of using 30 a single piston in connection with the stator shown, the stator may be in the form of a circle subdivided into chambers and a series of pistons placed therein to perform their functions in succession, whereby the rotor 35 is operated.

While I have shown and described the engine operating with a fuel gas under pressure, it is obvious that a four cycle construction is within the scope of my invention 40 wherein gas may be first sucked into a compartment, then compressed, exploded and exhausted.

Referring to Figs. 5 and 6 of the drawings, I have shown another form of my invention wherein the power imparted to the piston is not only transmitted by a friction shoe mechanism to the rotor but is also transmitted to said rotor through a clutch mechanism connecting the piston and main 45 shaft of the engine. In this modified form of my invention the structural features together with the valve mechanism may be practically of the same type as that shown in connection with Figs. 1 to 4 inclusive. 50 In order to prevent breakage of the engine due to back-fire, the chamber in the stator, as shown in Fig. 1 of the drawings, may be provided with adjustable spring-controlled relief valves *d*. In this form of my invention 55 the shaft 5 is free to revolve and carries the load and it is also understood that the rotor may be utilized as a pulley, whereby the power can be transmitted as well as at the shaft. The piston 6 is arranged to actuate 60 the rotor by the friction mechanism 65

similar to that shown in Figs. 1 to 4 of the drawings, but the hub 6' of said piston in this instance is arranged to revolve loosely upon the shaft 5 and any form of clutch mechanism may be employed to impart motion to the power-shaft 5. In the drawings, I have shown a clutch mechanism comprising a clutch tumbler 27 which is housed in the piston-hub and is adapted to engage recesses 27' that are formed in the shaft. 70 Thus when the rotor moves from right to left on its working stroke, the clutch tumbler 27 will grip the shaft and cause the shaft to rotate in the same direction. Upon the idle stroke of the rotor the clutch tumbler will be 80 free to ride over the notched surface of the shaft 5 until such time as it nests into a notch of said shaft, whereby another working stroke is effected and the shaft will be carried forward in a similar manner. Thus 85 a series of impulses to the rotor will cause the shaft to revolve in the same direction as the working stroke of said piston.

In order to provide some means for operating the valves, in the embodiment of the 90 invention shown in Figs. 5 and 6 of the drawings, I employ a sleeve member 28, which sleeve member is secured in any manner to the hub of the piston and projects outside of the housing 1 and the external end of 95 the sleeve carries the tappet-arm 22. The drawings illustrate the drive-shaft 5 as being provided with a pulley whereby power is transmitted to any source desired but it is understood that any form of gear other than 100 the pulley may be employed for the purpose mentioned. Thus with two connections for driving purposes, the power may be ultimately transmitted from the engine to two driven elements or I may, without departing 105 from the spirit of said invention, employ a clutch mechanism in connection with the shaft and piston only, whereby the power from the piston will drive the shaft and the friction mechanism and its associated rotor 110 may, in this case, be dispensed with, under which conditions the chamber carrying the piston would be closed.

I claim:

1. A gas engine comprising a chambered 115 stator having a circular outer wall provided with a slot therein, a rotor mounted about the stator, an oscillatory piston within the chamber, a clutch shoe engageable with the rotor, means extending through the chamber 120 slot connecting the shoe and piston, and means for alternately introducing and exhausting charges of gas into the chamber upon opposite sides of the piston.

2. A gas engine comprising a chambered 125 stator having a circular outer wall provided with a slot therein, a rotor mounted about the stator, an oscillatory piston within the chamber, a clutch shoe engageable with the rotor, means extending through the chamber 130

- slot connecting the shoe and piston, means under control of movement of the piston for admitting gas on opposite sides of the same, and means for exploding the gas controlled 5 by movement of said piston.
3. A gas engine comprising a chambered stator having a circular outer wall provided with a slot extending therethrough and an exhaust port in communication with said 10 chamber intermediate of its ends, a rotor mounted about the stator, a shaft journaled in the stator, a segmental piston within the chamber, a friction shoe mounted in the stator slot engageable with the rotor, a knuckle 15 block connecting the friction shoe and piston, and means for alternately introducing and exhausting charges of gas into the chamber upon opposite sides of the piston.
4. A gas engine comprising a chambered 20 stator having a circular outer wall provided with a slot extending therethrough and an exhaust port in communication with said chamber intermediate of its ends, a rotor mounted about the stator, a shaft journaled in the stator, a segmental piston within the 25 chamber, a friction shoe mounted in the stator slot engageable with the rotor, a knuckle block connecting the friction shoe and piston, valve-controlled ports in communication 30 with the stator chamber upon opposite sides of the piston, actuating levers for the valves, and an arm movable with the piston for operating the valve levers.

5. A gas engine comprising a chambered stator having a circular outer wall provided 35 with a slot therein, a rotor mounted about the stator, an oscillatory piston within the chamber, means extending through the chamber slot connecting the rotor and piston, means under control of movement of the 40 piston for admitting gas on opposite sides of the same, and means for exploding the gas controlled by movement of said piston and by movement of the rotor.

6. A gas engine comprising a chambered 45 stator having a circular outer wall and an exhaust port in communication with said chamber intermediate of its ends, a shaft constituting a rotor journaled in the stator, a segmental piston mounted upon the shaft 50 within the chamber, clutch mechanism associated with the piston for imparting motion to the rotor, valve-controlled ports in communication with the stator chamber upon opposite sides of the piston, actuating 55 levers for the valve, and an arm movable with the piston for operating the valve levers.

In testimony that I claim the foregoing I have hereunto set my hand at Manitowoc, 60 in the county of Manitowoc and State of Wisconsin, in the presence of two witnesses.

HENRY G. KRESS.
